UNITED STATES PATENT OFFICE

BERT E. HINKLE, OF HILSDALE, MICHIGAN, ASSIGNOR TO HILSDALE SCREEN COMPANY, OF HILSDALE, MICHIGAN, A CORPORATION OF MICHIGAN

WINDOW SCREEN

Application filed August 18, 1928. Serial No. 300,436.

My invention relates to window screens comprising sections which are slidably connected for adjustment to fit in window openings of different widths, and has reference 5 more particularly to the manner of fastening the screen wire into the screen frame.

In screens of this character, light wooden frames are employed in which the screen wire is secured, and the side strips or stiles of 10 one section are slidably connected with the side strips or stiles of the other section, the screen wires of the sections being overlapped, and the overlying edge of the screen wire of each section being secured to a cross brace 15 or edge binding member which extends between the stiles and serves as a filler between the screen wire of the sections to close the gap therebetween.

The screen wire is preferably secured to the 20 stiles with a strip, preferably integral with the stile, overlying the edge portion of the screen wire and fastened down to the stile with fasteners which engage through the edge portion of the screen wire. This strip is usually 25 quite thin and arranged at the side of the stile next to the stile of the other section with which it is slidably connected, and the fasteners are inserted therethrough from that side. With this construction it is not only 30 desirable to employ fasteners which will hold the strip and edge of the screen wire securely in place, but it is also important to provide fasteners of suitable character and arranged in such a manner that they will not at any 35 time annoy the user or subject the light frames to excessive strains by catching or interfering with the free and easy sliding operation of the sections. This is accomplished in my present construction by using staples 40 to fasten the strips in place, and the staples are not only arranged diagonally to the line of movement of the sliding sections but the staples of the two stiles which are slidably connected, are arranged in opposite diagonal 45 directions to the line of sliding movement, so that they approach one another at a suitable angle to facilitate passing and to avoid interference with one another and cramping in the sliding engagement of the sections.

50 This also affords an arrangement whereby

the staples straddle the grain of the wood with the two prongs of the staple located so as to give a double connection of maximum holding effect.

The principal objects of my invention are 55 to provide an improved screen of sliding sections; to fasten the screen wire securely to the frames; to apply the fasteners in such a manner that they cooperate more effectively with the fastening strip in holding the screen wire 60 in place; to avoid interference by the fasteners in the sliding movement of the sections; to arrange the fasteners so that they have a reciprocal guiding action in passing; and in general to provide a simple, convenient and 65 economical fastening for accomplishing the above objects.

On the drawing:—

Fig. 1 is a plan view of the screen;

Fig. 2 is an edge view thereof;

Fig. 3 is an enlarged section on the line 3—3 of Fig. 1;

Fig. 4 is an enlarged section on the line 4—4 of Fig. 1;

Fig. 5 is an enlarged fragmentary section 75 on the line 5—5 of Fig. 1; and

Figs. 6 and 7 are views showing the relative positions of the staples of the two sections in their crossing movements.

The screen shown and described herein is 80 similar to that of Patent No. 972,481, of October 11, 1910, to Sprague, and comprises two sections 1 and 2 of screen wire supported in separate frames which are slidably connected, with the screen in sections 1 and 2 overlapping, to vary the size of the screen to fit in different window openings.

The frame of the screen section 1 comprises two stiles 3—3 connected at their outer ends to an end rail 4 in any convenient manner, 90 and the frame of the screen section 2 comprises the stiles 5—5, which are likewise connected at their outer ends to the end rail 6. The frames of the two sections are of like 95 width and length, and have their stiles formed for sliding interengagement, the stiles 5 being provided in the inner faces, next to the stiles 3 with longitudinally extending rabbits or grooves 7 having an undercut recess 8 as illustrated in Fig. 4, while the stiles 3 100

- are provided on the inner faces next to the stiles 5 with a longitudinal rib 9 fitting to slide freely in the groove or channel 7 and a laterally extending flange 10 likewise fitting in the under cut recess 8 of the stile 5. Thus when the inner ends of the two frame parts are brought together, the ribs and flanges 9—10 will fit into and slide within the corresponding grooves and undercut recesses 7—8, 10 the engagement of the flanges 10 in the undercut recesses 8 preventing the two frame parts from separating laterally and the ribs 9 in the grooves 7 holding the frames in constant parallel relation.
- 15 For securing the screen wire sections 1 and 2 in the frames, the inner edge of each of the stiles 3—3 and 5—5 have formed therein a deep narrow slot or kerf 11 adapted to receive the edge of the wire screen cloth. These 20 slots or kerfs, which are merely wide enough to receive the edge of the screen wire freely therein in assembling, are located quite close to the inner or adjoining faces of the stiles 3 and 5, so as to provide a thin lip or strip 12, which is adapted to be clamped down by suitable fasteners against the screen in the slot or kerf 11, and to provide a definite line along which the lip 12 may bend when clamped down and to avoid breaking or splitting 25 of the wood at undesirable places, the lip is preferably scored at 13 along the inner extremity thereof or at the inner edge of the slot or kerf 11 as shown in Fig. 4.
- The fasteners for securing the edge of the 30 screen wire in the slots 11 are passed through the lips 12 from the inside to anchor the ends thereof in the thicker portion of the wood and also to avoid impairing the outer finished surface of the screen. The inner ends 40 of the fasteners are therefore located on the contiguous sliding surfaces of the screen frame sections, and if not fully driven in, or if they loosen up, are likely to catch and interfere with the desired free and easy sliding 45 movement of the frame sections, thereby causing annoyance and imposing excessive strain on the light marginal frames.
- In order to insure a more substantial fastening of the screen wire in the frames, and 50 to avoid catching of the fasteners even though they are not fully driven in or loosen up somewhat, I employ staples 14 and 15 respectively on the sections 1 and 2 which are wide enough to straddle a substantial portion 55 of the lip 12, and I arrange these staples diagonally so that the loop or bight portion 16 extends across the grain of the wood with the prongs 17 thereof in different strata to minimize the danger of splitting.
- 60 Moreover I arrange the staples 14 and 15 of the two adjoining stiles in opposite diagonal directions as shown in Figs. 1 and 6, so that in passing over one another they do not approach and pass in parallel relation but at a suitable angle as shown in Fig. 6, so that the

corresponding ends come together first. The staples are formed preferably of round wire, and in bending the prongs or arms 17 downwardly from the center or bight portion 16 and driving the staples, round bends 18 are 70 formed at the corners and the center portion usually arched somewhat as shown in Fig. 7, so that the ends of the bight portion 16 or corners 18 are usually pretty well embedded in the lip 12, and by arranging the staples 75 of the two stiles in opposite diagonal directions the rounded and depressed portions 18 of the opposite staples come together first, so that they start to pass quite readily even though the staples are not fully driven in, and 80 the criss cross or angular arrangement of the bight portion 16 affords a reciprocal guiding action to facilitate passing of the staples over one another.

The screen wire may be secured to the end 85 rails 4 and 6 in any convenient manner, for example by inserting in a slot 19, the ends of which receive tenons of the stiles 3 or 5 with a strip 20 filling in the extra space in the slot 90 between the stiles and held in place by fasteners 21 which pass through the end portion of the screen wire in the slot. The remote edges of the screen sections 1 and 2, which overlap one another, are each confined in a folded metal marginal binding strip 22, the 95 ends of which are secured in the kerfs or slots 11 of the respective stiles 3—3 or 5—5 to afford a cross brace for the frame, and the portion of this marginal binding 22, between the stiles is bent into an angular form as 100 shown in Fig. 5, to stiffen the cross brace and afford a flange 23 to close the space between the screens and prevent insects entering therethrough.

With this construction the screen wire not 105 only may be securely fastened in light wooden frames, but the annoyance and excessive strains occasioned by the fasteners along the stiles catching and interfering with the sliding of the sections is avoided, as the fasteners ride over one another freely and easily even though they are not fully driven in or have pulled out slightly.

While I have shown and described my invention in a preferred form, I am aware that 115 various changes and modifications may be made without departing from the principles of my invention, the scope of which is to be determined by the appended claims.

I claim as my invention:

1. In a screen of the class described, the combination of a pair of frames each having spaced side members slidably connected respectively with the spaced side members of the other frame for relatively adjusting said frames to vary the size of the screen, a section of screen wire in each frame slidably overlapping the section of screen wire in the other frame, a strip overlying the internal edge portion of each side member of each 120

125

130

frame with a lateral edge portion of the respective screen section interposed therebetween, and staples engaged through each strip and the edge portion of the screen section thereunder and engaged in the internal edge portion of the respective side member for securing the screen wire to the side member, said staples having the exposed bight portions thereof located between the slidably connected side members and arranged diagonally to the line of movement of said side members.

2. In a screen of the class described, the combination of a pair of frames each having spaced side members slidably connected respectively with the spaced side members of the other frame for relatively adjusting said frames to vary the size of the screen, a section of screen wire in each frame slidably overlapping the section of screen wire in the other frame, a strip overlying the internal edge portion of each side member of each frame with a lateral edge portion of the respective screen section interposed therebetween, and staples engaged through each strip and the edge portion of the screen section thereunder and engaged in the internal edge portion of the respective side member for securing the screen wire to the side member, said staples having the exposed bight portions thereof overlying the aforesaid strips at the opposed inner sides of the slidably connected members and the bight portions of the staples of one of said members being arranged at an angle to the bight portions of the staples of the other member with which it is slidably connected so that in the relative sliding movement of the slidably connected members the bight portions of the staples of each member pass the bight portions of the staples of the other member at an angle.

3. In a screen of the class described, the combination of a pair of frames each having spaced side members slidably connected respectively with the spaced side members of the other frame for relatively adjusting said frames to vary the size of the screen, a section of screen wire in each frame slidably overlapping the section of screen wire in the other frame, a binding on the overlapping edge of each screen section and having the ends thereof secured to the spaced side members of the respective frame, said binding between the side members comprising integral angular strips of sheet metal nested together with an angular edge of the screen section secured therebetween, kerfs in the inner edges of the side members forming strips on and integral with the side members of each frame and overlying the lateral edge portions of the respective screen section, said strips being scored along their inner edges, and staples engaged through each strip beyond the score and through the edge portion

of the screen section thereunder for securing the screen wire to the side members, said staples having the exposed bight portions thereof overlying the strips at the opposed inner sides of the slidably connected members and the bight portions of the staples of one of said members being arranged at an angle to the bight portions of the staples of the other member with which it is slidably connected so that in the relative sliding movement of the slidably connected members the bight portions of the staples of each member pass the bight portions of the staples of the other member at an angle.
